DESIGN FOR A DOOR LATCH HOUSING OR SIMILAR ARTICLE

Thomas Irving Potter, New York, N. Y.

Application December 31, 1947, Serial No. 143,471

Term of patent 14 years

(Cl. D50—5)

To all whom it may concern:

Be it known that I, Thomas Irving Potter, a citizen of the United States of America, residing in the Borough of Manhattan, city of New York, county of New York, and State of New York, have invented a new, original, and ornamental Design for a Door Latch Housing or Similar Article, of which the following is a specification, reference being had to the accompanying drawing, forming part thereof:

Fig. 1 is a front elevational view of a door latch housing showing my new design.

Fig. 2 is an end elevational view of the door latch housing as seen from the left of Fig. 1.

Fig. 3 is a top plan view of the door latch housing shown in Fig. 1.

Fig. 4 is a perspective view of the door latch housing shown in Fig. 1.

I claim:

The ornamental design for a door latch housing or similar article, as shown.

T. IRVING POTTER.
